UNITED STATES PATENT OFFICE

SIEGFRIED HELD, OF BENTON HARBOR, MICHIGAN, ASSIGNOR TO OIL GAS GENERATOR CORPORATION, OF CHICAGO, ILLINOIS, A CORPORATION OF ILLINOIS

OIL-GAS GENERATOR

Application filed November 9, 1925. Serial No. 67,756.

The invention relates to an improved method of and means for converting oil into fixed gas.

One of the objects is to provide simple, inexpensive and automatic means for converting oil into gas that may be stored for future use, and which may be done without requiring any movable parts or manual supervision.

10 Another feature of the invention is the method of procedure whereby the aforesaid beneficial results may be obtained.

A further object is to simplify and cheapen the cost of construction and make it adaptable 15 for household use.

Another object is to distill the oil to produce a vapor and to redistill the condensate, which will issue from a condenser included in the system, so long as said vapor is condensed, 20 by causing said condensate to be returned automatically by effect of gravity, to the path through which the vapor previously passed.

Other and further important objects of this invention will be apparent from the disclosures in the specification and the accompanying drawings.

This invention (in a preferred form) is illustrated in the drawings and hereinafter more fully described.

25 On the drawings:

Figure 1 is a plan view of the oil gas generator.

Figure 2 is a side elevation thereof.

Figure 3 is an enlarged central vertical 30 section taken on line III—III of Figure 1.

Figure 4 is an enlarged broken away section taken on line IV—IV of Figure 1.

Figure 5 is a reduced side elevation of the device shown in Figure 4 at right angles 35 thereto.

Figure 6 is a plan view taken looking down from line VI—VI of Figure 3.

Figure 7 is a plan view of the double gas 40 burner shown in section in Figure 3.

Figure 8 is a plan view of the vapor superheater shown in section in Fig. 3 immediately above the smaller burner.

Figure 9 is a transverse section taken on 45 line IX—IX of Figure 2.

Figure 10 is a section taken on line X—X of Figure 2.

In all of the views similar reference numerals indicate similar parts.

As shown on the drawings:

The reference numeral 15 denotes an oil pump which takes the oil to be made into a fuel gas from a suitable reservoir, not shown, through the pipe 16 and forces it under suitable pressure, about 15 pounds to the square inch, through pipe 17^a, conduit 17 and pipe 18, (Figure 3) into the dome-shape casing 19 of the vaporizer 20. The oil may strike the inner surface 21 of the vaporizing chamber 20, which at this time has been suitably heated, 60 and will flash into a vapor. The heavier components of the oil which are not initially vaporized will be caught by the terraced cone 22 and by the closure disk 23 where it will be further heated to produce the further vaporization. Some of the lighter constituents of the oil may be vaporized while passing through the conduit 17 and the pipe 18 before it reaches the vapor chamber 20, as oil.

When the pressure is not great, the inflowing oil may fill the cup 24, which is screwed upon the upper end of pipe 18 and overflow and cascade over the terraced surface of the cone 22. Only relatively small quantities of oil are injected into chamber 20 at any one 70 time so that at no time does this chamber contain a large quantity of oil. At no time does oil, as such, flow from the vaporizer. The vaporizer 20 receives oil and ejects vapor therefrom.

It will be observed that the surface 25 of the floor or closure 23 tapers inwardly and upwardly toward openings 26, through which the vapor finds exit into the conduit 27 from which it passes into the superheater 28. The 80 vapor passes through a spirally arranged path 29, shown in broken lines in Fig. 8, from the conduit 27 and through the nipple 30 to the separator 31 (Figure 4). The nipple is connected to the separator 31, as shown at 85 32, in communication with the chamber 33.

When the fluid, which may be a mixture of oil vapor and gas, reaches this chamber the lighter constituents will pass upwardly through the openings 34 and strike the baffle 100

walls 35 in the chambers 36—36. Any liquid constituent which the confluent contains at its then temperature is precipitated upon cooling and by effect of gravity it will pass 5 through the ports 34—34 into chamber 33 and through the nipples 37—37 into the chamber 38 and into the inner circular conduit or vaporizer 39 of the regenerator 40, as shown in broken lines in Figure 6, where it is again sub- 10 jected to heat and revaporized, and then returned to chamber 33 to again pass upwardly into chamber 36.

Noting the further progress of the fluid upwardly from chamber 36, after it strikes 15 the baffles 35, it will pass successively through a series of vertically arranged chambers 36, 36^a, 36^b, and 36^c, and in which it will strike baffles 35, 35^a, 35^b and 35^c, successively, through ports 34^a, 34^b, 34^c and 34^d. In each 20 of the chambers 36 more or less liquid is released from the rapidly moving fluids by cooling and by impact against the baffles 35 in the respective chambers and gravitates into and through the paths heretofore described and 25 passed upwardly through the chambers 36 and ports 34 on its way to chamber 41. From this chamber the heavier constituents that may be liberated by reduction of temperature will likewise pass downwardly through the 30 series of chambers to be again heated and returned to the chamber 41.

The vapor in chamber 41 will now pass through the coiled condenser pipe 42 in which it will be further cooled and condensed to 35 some extent. This pipe is coiled to provide a larger surface exposed to the atmosphere and a straight branch 43 leads into chamber 44 of the separator from which the gas and vapor pass through the nipple 45 into the 40 fixing chamber 46 of the regenerator 40 to be there volatilized and fixed.

The regenerator 40 is heated by the burner 52 which is immediately therebelow. From 45 the fixing chamber 46 of the regenerator 40 the gas passes into the vertical chamber 47 and from thence it is conveyed by a suitable pipe 48 to an oil gas holder (not shown).

Gas is taken from chamber 47 by the pipe 49 and fitting 50 to the gas inlet nozzle 51 for the burners 52 and 53, shown in plan in Figure 7.

A gas chamber 56 supplies both of these burners. A needle valve 54 controls the supply of gas to the burners and the slidible sleeve 55 having a handle 55' regulates the amount of air admitted through slots 51^a in the nozzle 51 into gas chamber 56.

The burner 53 directly heats the vaporizer 50 casing 19 and the superheater 28 and the burner 52 directly heats the regenerator 40. The term regenerator has been given to the structure 40 to conveniently distinguish the structure in which the chambers or conduits 38 and 46 are formed, and which struc- 65

ture is heated by the burner 52 immediately therebelow.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. In an oil gas generating apparatus, a dome-shaped oil vaporizing chamber having a cone-like bottom, open at its axis, a terraced cone inside of the dome, an oil inlet pipe extending into the vaporizing chamber and through the terraced cone, a cup secured to the upper end of the pipe, a superheater structure for superheating the oil vapors, said superheater structure being positioned below the dome and connected with the axial opening therein, and heating means below the superheater structure to heat the superheater structure and the vaporizing chamber.

2. In an oil gas generating apparatus, a dome-shaped oil vaporizing chamber having a cone-like bottom open at its axis, a terraced cone inside of the dome, an oil inlet pipe extending into the chamber and through the terraced cone, a cup secured to the upper end of the pipe, a superheater structure for superheating oil vapors, said superheater structure being positioned below the dome and connected with the axial opening therein, heating means comprising a burner positioned below the superheater structure to heat said structure and the vaporizing chamber, a revaporizer below the superheater structure, a separator in communication with the superheater structure and the revaporizer, and heating means comprising a burner positioned under the revaporizer.

3. In an oil gas apparatus, a unitary structure comprising a revaporizer, a superheater, and a vaporizing chamber in superimposed spaced relation to and in communication with each other, and heating means comprising burners positioned below the revaporizer and the superheater respectively.

4. In an oil gas apparatus, a unitary structure comprising a fixer, a superheater, and a vaporizing chamber in superimposed spaced relation to and in series connection with each other, means for heating the structure, and means connecting the fixer and the heating means.

5. An oil gas apparatus, a unitary structure comprising a vaporizing chamber, a superheater below the vaporizing chamber and in communication therewith, a revaporizer below the superheater, a separator in communication with the revaporizer and the superheater, and means for heating the revaporizer, the superheater and the vaporizing chamber.

6. An oil gas apparatus, a unitary structure comprising a vaporizing chamber, a superheater in communication therewith, a revaporizer, a separator in communication with the revaporizer and the superheater, a fixer connected with the separator, and means for heating the fixer, the revaporizer, the superheater and the vaporizing chamber.

5
7. In an oil gas apparatus, a unitary structure comprising a vaporizing chamber, a superheater, a casing having revaporizing and fixing chambers formed therein, and means for heating the said casing and the said superheater and the said vaporizing chamber, the said vaporizing chamber, said superheater, and said casing being positioned in superimposed spaced relation to, and in communication with, each other.

10
20
25
8. In an oil gas apparatus, a vaporizer, a superheater, a separator, a condenser, a casing having a pair of chambers therein adapted to respectively revaporize and to fix hydrocarbons therein, means connecting the vaporizer, the superheater, the separator and the condenser being in communication with the chambers in the casing, and means arranged to heat the casing.

In testimony whereof I have hereunto subscribed my name.
